UNITED STATES PATENT OFFICE.

JOHN BALD, OF LOUISVILLE, KENTUCKY.

HARNESS-BIT.

No. 804,447.

Specification of Letters Patent.

Patented Nov. 14, 1905.

Application filed April 17, 1905. Serial No. 256,004.

To all whom it may concern:

Be it known that I, JOHN BALD, a citizen of the United States, residing at Louisville, in the county of Jefferson and State of Kentucky, 5 have invented a new and useful Harness-Bit, of which the following is a specification.

This invention relates to harness-bits.

The object of the invention is to provide an overcheck harness-bit which shall in a humane and positive manner operate positively to restrain a restive horse, prevent tossing of the head, side pulling, and the taking of the bit between the teeth.

With the above and other objects in view, 15 as will appear as the nature of the invention is better understood, the same consists in the novel construction and combination of parts of an overcheck harness-bit, as will be hereinafter fully described and claimed.

20 In the accompanying drawings, forming a part of this specification, and in which like characters of reference indicate corresponding parts, Figure 1 is a view in perspective exhibiting the bit of the present invention applied 25 to a horse. Fig. 2 is a perspective detail view of the bit. Fig. 3 is a view in vertical transverse section through the bit.

The bit is by preference constructed of a single piece of material and comprises two 30 mouth-plates 1, with each of which is combined a downwardly and outwardly curved lever 2, provided on its under side with a perforated ear 3 and longitudinally of its length with a slot 4 to receive the driving-

35 reins. Combined with the mouth-plates are two bit-bars 5 and 6, which, as shown in Fig. 3, are approximately oval in cross-section and occupy a plane substantially coincident to that of the under side of the lever, the bars being

40 connected with the mouth-plates by extensions 7, which are disposed in alinement with the said plates. The bit-bars, as shown in Fig. 2, are the thickest at their center and gradually taper toward their ends, thereby to secure a 45

spring action, and the intermediate portions of the bars are bulged outward away from each other, thereby to give to each bar an approximately bow shape when viewed in plan. The upper end of each mouth-plate is provided 50 with an orifice 8, which is shown in Fig. 2 and 3 as approximately V-shaped, although this contour is not essential and may be changed, if desired, the upper wall of the opening forming a bar 9, upon which is mounted a tubular 55 roller 10.

When the bit is attached to a bridle, the

orifices 8 are engaged by a nose-band 11, the terminals of which project through the orifices, each terminal of the band being provided with a buckle 12, (one only being shown,) 60 the buckles being engaged by the terminals 13 of a draw-strap 14, which is bifurcated for the purpose and fastens over the head through suitable guides (not shown) on the guide-piece 15 and connects at its free end with a 65 check-strap 16 of the common or any preferred construction, which, as usual, is connected with the turret-hook 17 of the saddle. The draw-strap 14 has combined with it a pad 18, preferably of leather, which is furnished 70 with a keeper 19, preferably formed from a part of the pad, and through this keeper projects an ordinary adjusting-strap 20, one end of which is sewed or otherwise secured to the nose-band, as at 21, and is connected in any 75 suitable manner to the check-strap. By the provision of the nose-band, draw-strap, and adjusting-strap the bit is held positively positioned in the horse's mouth, and by the employment of the rollers 10 the nose-strap will 80 be free to slide within the orifices 8, whereby when the horse attempts to throw down his head the bit will be forced upward in his mouth and then stop the motion. The ears 3 are engaged by a chin-rest 22, which may 85 be either a chain, as shown, or a strap, as may be preferred, and this chin-rest will operate to force the bit against the roof of the animal's mouth should it open its mouth in an attempt to take the bit. 90

By having the bit-bars formed in the manner described—that is, outwardly bulged relatively to each other—they will be caused to conform accurately to the animal's mouth and will without causing pain be thoroughly effective in checking the animal should it become fractious. Moreover, this construction will permit the bit-bars to yield, and thus eliminate pain, when the reins are sharply drawn upon, while in no wise detracting from 100 the checking action of the bit. 95

Having thus described the invention, what is claimed is—

1. An overcheck harness-bit embodying a pair of bit-bars, the intermediate portions of which are outwardly bulged and the terminals of which are reduced to secure a spring action. 105

2. An overcheck horse-bit embodying a pair of mouth-plates each of which carries a downwardly and outwardly curved lever, and a pair of bit-bars carried by the plates, the interme- 110

diate portions of which are outwardly bulged and the terminals of which are reduced.

3. An overcheck horse-bit embodying a pair of mouth-plates each of which carries a downwardly and outwardly curved lever, and a pair of bit-bars integral with the plates, the intermediate portions of which are outwardly bulged and the terminals of which are reduced.

4. An overcheck-bit embodying in an integral structure a pair of mouth-plates each of which carries a downwardly and outwardly curved lever, the upper portion of each plate

being provided with an orifice and with a bar carrying an antifriction-roller, and a pair of bit-bars combined with the plates and having intermediate outwardly-bulged portions and reduced terminals. 15

In testimony that I claim the foregoing as my own I have hereto affixed my signature in the presence of two witnesses.

JOHN BALD.
